DESIGN FOR A TOY JACK-IN-THE-BOX

William Smith, New York, N. Y.

Application August 25, 1947, Serial No. 141,057

Term of patent 3½ years

(Cl. D34—15)

To all whom it may concern:

Be it known that I, William Smith, a citizen of the United States, residing at New York, county and State of New York, have invented a new, original, and ornamental Design for Toy Jack-in-the-Box, of which the following is a specification, reference being had to the accompanying drawing, forming part thereof.

Figure 1 is a top plan view of my toy jack-in-the-box in open position.

Figure 2 is a front elevation of my toy jack-in-the-box in open position.

Figure 3 is a side elevation of my toy jack-in-the-box in open position, showing my new design.

I claim:

The ornamental design for a toy jack-in-the-box, as shown.

WILLIAM SMITH.
